UNITED STATES PATENT OFFICE.

FARNHAM YARDLEY, OF NEW YORK, N. Y., ASSIGNOR TO JENKINS BROS., OF NEW YORK, N. Y., A CORPORATION OF NEW JERSEY.

VALVE-OPERATING MECHANISM.

Application filed October 8, 1921. Serial No. 506,518.

To all whom it may concern:

Be it known that I, FARNHAM YARDLEY, a citizen of the United States, residing in the city of New York, county of New York, 5 and State of New York, have invented certain new and useful Improvements in Valve-Operating Mechanism; and I do hereby declare the following to be a full, clear, and exact description of the invention, such as 10 will enable others skilled in the art to which it appertains to make and use the same.

The invention relates to a mechanism for operating reciprocating valves of the quick action type and has for its object to provide a simple and efficient attachment to be applied to valves of the type indicated, adapted to operate the valve by a single direct movement and to hold the valve securely in its adjusted position. To this end the 15 invention comprises a bracket arm having a perforated foot portion adapted to surround the neck of the valve casing and a curved and bifurcated or forked outer portion terminating in perforated ears which overlie 20 the foot portion, said ears receiving a pivot or screw upon which is mounted a hand lever having a lateral cam face adapted to engage and operate the stem of the valve, and a flat end section, preferably provided with 25 a depression therein to engage the end of the valve stem and hold the valve securely in its adjusted position, said hand lever also being provided with a lug, or lugs, adjacent its pivotal connection with the bracket, 30 adapted to engage the curved portion of the bracket arm to limit the movement of the hand lever.

The accompanying drawing is a vertical elevation, partly in section, of the device as 35 applied to a spring closed valve of the quick action type.

Referring to the drawing, 1 indicates the valve casing, having a bottom cap or closure 40 2, carrying a helical spring 3 which serves normally to force valve 4 to its seat, the valve being normally unseated by means of a reciprocating stem 7 slidably mounted in the neck 5 of the valve casing. Said neck 5 is provided with external screw threads to 45 receive a cap of a gland or stuffing box 6, and also to serve in conjunction with nut 10 as means for locking the operating mechanism to the valve casing.

The support for the operating mechanism 50 comprises a bracket arm 8 provided at its

lower end with a laterally disposed perforated foot 9, which fits over the neck 5 of the valve casing and rests upon the annular shoulder formed about the base of the neck. The upper end of the bracket arm is curved laterally and is bifurcated or forked, the two arms 11 of the forked portion being provided with perforated ears 12 which overlie the foot portion 9, and are adapted to receive a pivot bolt 17.

Journaled on the pivot bolt 17 is a hand lever 13 having an eccentric cam surface 14 on one face disposed laterally of the pivot connection, and a relatively flat end face 15 provided with a transverse notch or recess 16, the cam surface 14 serving to engage the outer end of the valve stem 7 and force the stem inwardly to unseat the valve, when the lever 13 is swung outwardly, upon its pivot, with respect to the valve, and the notch 16 serving to lock the lever and the valve in their adjusted positions, when the lever is swung into substantial axial alignment with the valve stem.

In order to hold the lever 13 in its inoperative position and substantially normal to the longitudinal axis of the valve stem, said lever is provided with a lug 18 adjacent the pivotal connection with the bracket, which lug is adapted to engage the inner edge of the curved portion 11 of the bracket arm and arrest the movement of the lever 13, when the latter reaches the position indicated in the figure of the drawing. If desired a lug 18 may be applied on each face 80 of the lever.

The bracket arm is secured to the valve casing by passing the foot member 9 over the neck 5 and locking said foot member to the casing by means of the set nut 10 engaging the screw threads on the neck 5. This means of attachment admits of the bracket 8 being set in any desired angular relation with respect to the valve stem, so that the hand lever may project or extend 95 outwardly from the valve in any desired direction and the bracket and hand lever locked in the selected adjusted position.

While the invention has been illustrated as applied to a normally spring closed valve, it will be obvious that it may also be applied to a valve which is normally open but which is adapted to be closed by the engagement of the cam surface on the hand lever 13 engaging the upper end of the valve stem.

What I claim is:

1. In a valve, a valve casing having a neck portion, a valve operating mechanism comprising a bracket arm having a perforated foot to engage the neck of the valve casing and a curved and forked outer end having perforated ears overlying the foot a nut on the neck of the valve casing to engage and lock the foot of the bracket to the valve casing, and a hand lever pivoted in said ears having a lateral cam surface adapted to engage and depress the valve stem, and a flat end surface to hold the valve stem in adjusted position.
- 15 2. In a valve, a valve casing having a neck portion, a valve operating mechanism comprising a bracket arm having a perforated foot to engage the neck of the valve casing and a curved and forked outer end having perforated ears overlying the foot, a nut on the neck of the valve casing to engage and lock the foot of the bracket to the valve cas-

ing, a hand lever pivoted in said ears having a lateral cam surface adapted to engage and depress the valve stem and a flat end surface having a depression therein cooperating with the valve stem to lock the latter in adjusted position.

25 3. A valve operating mechanism comprising a bracket arm having a perforated foot to engage the neck of the valve casing and a curved and forked outer end having perforated ears overlying the foot, a hand lever pivoted in said ears having a lateral cam surface adapted to engage and depress the valve stem and a flat end surface to hold the valve stem in adjusted position, said hand lever having a lug adjacent the pivotal connection with the bracket arm to engage the curved end of the latter to limit the 30 movement of said lever.

35 In testimony whereof I affix my signature.

FARNHAM YARDLEY.
